GEOGRAPHICAL CLOCK

Baudilio Diaz Martinez, Havana, Cuba

Application July 29, 1954, Serial No. 31,656

Term of patent 7 years

(Cl. D42—7)

Figure 1 is a front perspective view of the geographical clock showing my new design;

Fig. 2 is a front elevational view thereof;

Fig. 3 is a side elevational view; and

Fig. 4 is a rear elevational view.

I claim:

The ornamental design for a geographical clock, substantially as shown.
